INVENTOR

John P. Williams,
BY J. H. Lett

ATTORNEY

UNITED STATES PATENT OFFICE.

JOHN P. WILLIAMS, OF BAYSIDE, NEW YORK, ASSIGNOR TO DUPLEX ELECTRIC COMPANY, OF NEW YORK, N. Y., A CORPORATION OF DELAWARE.

AIR-VENT MEANS FOR VAULTS.

Application filed March 4, 1927. Serial No. 172,914.

This invention relates to air-vent means for vaults and comprises a device which is mounted in a vault wall and extends therethrough and is adapted to be operated from the inside of the vault to provide a direct opening to the exterior of the vault. The purpose of such air-vent devices is to enable anyone locked in a vault, either under burlarious attack or accidentally, to conveniently open up the air passage afforded by the device and thus secure desired ventilation within the vault and communication through the wall thereof. The air passage thus afforded will also enable the pumping of oxygen or air from the outside in sufficient degree to preserve the life of anyone imprisoned in the vault during any period of time until released.

It will be understood that bank vaults, as usually constructed, are air-tight at the interior, and have time-lock closure doors, and that therefore to preserve life within the vault under closed conditions it is necessary to provide emergency means for communication with the outside air.

Devices of this character as heretofore constructed have involved the use of a metallic sleeve extending through the vault wall, and a plug having an insertable position within the sleeve and forming a closure thereof, said plug being in threaded engagement with the interior of the sleeve and being adapted to be revolvably operated from the interior of the vault to enable its disengagement from threaded connection with the sleeve and the withdrawal of the plug inwardly from the sleeve to open up the air passage therethrough. This previous type of air-vent device is open to many objections and disadvantages, especially inasmuch as it requires heavy manual operation by the imprisoned person and the complete manual withdrawal of an essentially heavy plug, the general conditions of essential operation thus imposing upon an imprisoned person a heavy burden of manipulation and procedure to accomplish the operation of the device under a manifestly trying stress of conditions.

It is the object of my present invention to provide an improved device of the character above indicated which will not only require but slight and instant manipulation but which will be automatic in the instant ejection of the closure plug and the consequent automatic opening of the air passage. My

improvements are further designed to provide a device of this character which will possess advantages in point of simplicity, convenience, economy in construction, security, ease of operation, effectiveness, and general efficiency.

It will be understood that my improved air-vent means are adapted for effective employment through the walls of all types of vault construction, or large safes, or storage rooms or other compartments, under conditions in which an air-vent would be required to the interior in the eventuality of anyone being imprisoned therein.

In the drawings—

Figure 1 is a face view of a portion of the interior surface of a vault wall provided with my improved air-vent means.

Fig. 2 is a corresponding view at the exterior surface of the vault wall.

Fig. 3 is a longitudinal sectional view through a portion of the vault wall, showing the improved air-vent means partly in side view and partly in section.

Fig. 4 is a sectional view corresponding to Fig. 3 and extending sectionally through the air-vent means.

Fig. 5 is a detail cross-section on the line 5—5, Fig. 4.

Fig. 6 is a detail cross-section on the line 6—6, Fig. 4.

Fig. 7 is a detail cross-section on the line 7—7, Fig. 4.

Fig. 8 is a detail cross-section on the line 8—8, Fig. 4.

Fig. 9 is a detail cross-section on the line 9—9, Fig. 4.

Fig. 10 is a detail cross-section on the line 10—10, Fig. 4.

Fig. 11 is a detail cross-section on the line 11—11, Fig. 4.

Fig. 12 is a face view of the inner face of the operating spindle, showing its electrical connections.

Fig. 13 is a perspective view, partly in section, of the holder and bearing for the operating spindle, showing the electrical connections thereof.

Fig. 14 is a partial longitudinal sectional view corresponding to Fig. 3, and illustrating a modified construction in the mounting of the device upon steel-lined vaults.

Fig. 15 is a partial longitudinal sectional view corresponding to Fig. 3, and illustrating a supplementary extension means for

increasing the length of the air-vent means at its front end to compensate and equalize the length for vault walls which are of increased thickness beyond the standard length 5 of the device.

Corresponding parts in all the figures are denoted by the same reference characters.

Referring to the drawings, 18 designates the tube or sleeve which constitutes the main 10 tubular body of the device and extends longitudinally through the vault wall. The exterior surface of this tube is preferably cylindrical, and its outer end portion which is related to the outside surface of the wall 15 is preferably of increased exterior diameter, as at 19, and the lesser diameter beyond this enlarged end is uniform throughout the length of the tube, as at 20. An external circumferential shoulder, as at 21, is thus 20 formed upon the tube at the inner end of the enlarged front end portion 19. The internal bore or passage of the tube extends longitudinally and is preferably cylindrical with a diameter extending uniformly, as at 25 22, from the inner end of the tube, which is related to the inside surface of the vault wall, to a point within the enlarged outer or front end portion 19, at which point the bore is flared or tapered outwardly, as at 30 23, said flaring enlargement of the bore extending to the front end of the tube. The lesser diameter inner end portion 20 of the tube is exteriorly threaded, as at 24, the threads extending from the inner end of 35 the tube a suitable distance along its length.

In mounting the device within the vault wall, the tube or sleeve is surrounded by a concrete grout or filling which forms the interior wall mass, as at 25, and covers the 40 surface thereof including the exterior threads 24, and said threads are engaged by a locking member (as hereinafter described) secured at the inner face of the vault wall, whereby the tube is securely 45 set and locked in its position extending from the inner face to the outer face of the wall, any longitudinal movement of the tube being resisted by said locking member and the external shoulder 21 and external threaded 50 portion 24 which are embedded in the wall grout or filling, said shoulder co-acting with the locking member against longitudinal movement of the tube.

At suitable points, preferably upon the 55 enlarged front end portion 19, and upon the lesser diameter portion 20 between the threaded portion 24 and the shoulder 21, the tube is exteriorly provided with projecting ribs or lugs, as at 26, of suitable length and 60 at diametrically opposite sides, which ribs are engaged by anchoring plates, 27, mounted to surround the tube and project laterally therefrom, said plates having a central opening corresponding to the cylinder of the 65 tube and being provided with recesses, 28,

at opposite sides of said opening and corresponding to the retaining ribs 26. Said anchoring plates and retaining ribs are thus embedded in the concrete grout of the vault wall and are operative to anchor the tube or 70 sleeve in its set position and resist movement thereof either laterally or longitudinally.

29 designates the closure plug for the tube, which normally extends longitudinally within the bore of the tube and beyond the inner end thereof related to the interior surface of the vault wall. The outer or front end of the plug has a flared or tapered head, 30, corresponding to the flared end 23 of the tube and adapted to form a tight fit 80 therein, from which head a longitudinal stem, 31, extends and constitutes the main body of the plug. This stem is of reduced diameter with respect to the head 30 and to the diameter of the interior tube-bore 85 22, thus forming a shoulder, 32, at the rear or inner end of the flared head 30. The plug is preferably cylindrical, but is fixed against any turning movement within the tube, and it is preferably provided at the outer face 90 of its head 30 with a circumferential face-flange, 33, which projects, at the exterior surface of the vault wall, over the joint between the flared plug-head 30 and the flared end 23 of the tube-bore and forms a closure 95 thereof. The exterior surface of the plug-stem 31 is threaded, as at 34, from its extreme inner end related to the interior of the vault to a suitable distance of its length, and in said threaded portion a groove forming a key-way, as at 35, is provided, said groove being in the longitudinal plane of the plug.

36 designates the locking member, before mentioned, for the tube 18. This member 105 also forms the mounting and bearing for the operating spindle which controls the plug, and comprises a body plate, 37, which is secured to the inner face of the vault wall, preferably by screws, as at 38, entering 110 sockets, 39, fixed in the grout or mass 25 of the wall. Said body plate has a central aperture, 40, in alignment with the plug 29 and through which the threaded end of the latter passes, and surrounding said aperture is a tubular collar, 41, projecting from the inner face of the body plate and interiorly threaded, as at 42, said threads engaging the threaded inner end of the main tube 18 and thus locking the tube in its mounted 115 position. Projecting from the body plate 37 laterally within the aperture 40 is a key or stud, 43, which engages the key-way or groove 35 of the closure plug 29 and thus precludes turning of the latter when in secured normal position and when being released by turning of the operating spindle.

The locking member 36 comprises an extension at its outer face, to provide the support and bearing for the before-men- 130

tioned operating spindle. Said extension is constituted by a projecting collar, 44, through which the aperture 40 in the body plate 37 is extended as a bore, 45, forming a cylindrical bearing for the hub of the operating spindle, and the upper side of said collar is recessed, as at 46, to conform to the revoluble hub of the operating spindle, said recess intersecting the collar-bore 45 and in conjunction therewith forming a seat and bearing into and from which the hub of the spindle can be inserted for operation or lifted for disengagement.

The operating spindle hereinbefore mentioned is designated by 47 and preferably comprises a body disc, 48, from the periphery of which radiate a convenient number of handles, 49, affording finger or hand holds by which the spindle may be turned. From the inner face of the body disc extends a projecting cylindrical hub, 50, having an outwardly flared or beveled cylindrical end-head, 51, which hub and head are seated in the corresponding recess 46 and bore 45 of the locking member 36 and have their bearing therein, the beveled head preventing movement or detachment of the spindle in a longitudinal plane but the spindle being detachable when desired by lifting it from the hub-seat. The spindle hub is provided with a longitudinal bore, 52, internally threaded, as at 53, and engaging the threaded end 34 of the plug 29, whereby the latter is by operation of the spindle tightened up and secured in its normal closure position within the main tube 18.

54 designates a coiled spring which is provided for the automatic ejection of the plug 29 forwardly from the tube 18 when the spindle is operated at the interior of the vault to release its locked engagement with the plug. This spring is of sufficient tensile strength to ensure instant and effective ejection of the plug to throw it entirely clear of the tube, and it is mounted within the bore of the main tube and surrounds the longitudinal stem 31, bearing at its front end against the plug-shoulder 32 and at its rear end against the body plate 37 of the tube-locking member 36.

The main elements of the device, such as the tube and plug and locking member are formed of metal resistant to fire or ordinary means of attack, preferably steel, and the outer enlarged end 19 of the tube, as well as the tapered head 30 of the plug, are preferably rendered drill-proof. The joint between the plug head 30 and the flared front end 23 of the tube and the face flange 33 of the plug head is preferably sufficiently tight to preclude the ingress of air or liquid. Also, if desired, any suitable means may be provided to lock the operating spindle in set position, whereby accidental turning of the stem or release of the closure plug will be

precluded. The outer face of the body disc 48 of the operating spindle may also carry directions for turning or operation, as at 55, preferably in radium painted or printed letters, whereby the device and its means and method of operation can be located in the dark interior of the vault.

From the foregoing description, it will be understood that the device comprises in its main elements but five parts, viz: the body tube, the locking member for the tube, the closure plug, the operating spindle for the plug, and the plug-ejecting spring.

In Fig. 14 I have illustrated a modified construction in the mounting of the device upon steel-lined vaults, in which circumstances the body plate 37 of the locking member 36 is directly fastened to the face of the metal plate, 56, constituting the vault lining, the securing screws 38 directly engaging said lining plate, as at 57. This construction is adaptable to the usual conditions in a steel-lined vault, in which an air space, as at 58, exists between the inner face of the lining plate and the concrete grout or body mass 25 of the vault wall.

Referring to Fig. 15, I have illustrated an extension means whereby the operative length of the device may be increased to compensate for extra-thickness vault walls beyond the dimensions of the air-vent device in its usual standard length. In this connection, it will be understood that the improved air-vent devices are constructed in suitable lengths adapted to the ordinary standards of thickness of the walls in which the device is mounted, but that under some circumstances it may be desirable to provide a supplementary extension means to meet an extra thickness of wall without altering the length of the main elements and construction of the air-vent device. Such means, as herein illustrated, are provided by an extension tube, as at 59, preferably formed of copper or bronze, and fitting at its inner end, as at 60, over the front or outer end of the main body tube 18 at a point within the wall mass, from which mounting at its inner end the extension tube projects the required distance to the outer face of the vault wall, as at 61, and has its front end turned outwardly to form a face flange, 62, seated against the outer face of the wall mass 25. Within said extension tube is set an extension plug, 63, preferably of copper or bronze, which corresponds to the interior space of the extension tube between the end of the main tube or sleeve 18 and the end of the main plug 29 and the outer face of the vault wall. Said extension plug is preferably tubular, with a solid outer end wall, 64, thus affording an interior air-space, as at 65, and the inner end of said tubular body abuts over the joint between the tapered head 30 of the main plug 29 and the tapered end 23 of the bore

130

of the main tube 18. The extension tube thus provides a fire proof capping beyond the outer end of the main tube 18 and main plug 29 and constitutes an extension of the device to compensate for the full thickness of the vault wall, and it is secured in connection with and carried by the main plug 29, whereby it is in effect an extension of said main plug and will be automatically ejected therewith in the operation of the device. The connection just referred to is preferably effected by means of a threaded rod, 66, extending longitudinally in the air-space 65 and having a threaded connection with the end of the head 30 of the main plug 29, as at 67, and to the end wall 64 of the extension plug, as at 68. The outer face of said end wall 64 is preferably covered by a face plate, 69, preferably of drill-proof steel, which is 15 extended over the joint between the extension plug 63 and the extension tube 59, as at 70, thus forming an air and liquid proof joint. Said face plate is preferably secured to the extension plug by a threaded stem, 71, 20 in engagement with the end wall 64.

My improved air-vent device also comprises alarm mechanism for operating an alarm or signal when the spindle is actuated to release the main closure plug 29 and permit its automatic ejection from the wall tube 18. In carrying out this purpose, the locking member 36 is provided with contact means in an electric circuit, and the preferred construction comprises an insulating plate, 72, carried upon the outer face of the recessed collar 44 of the locking member, and in said plate, which is preferably formed of "bakelite", are mounted respectively at diametrically opposite sides of the spindle hub two projecting spring-actuated plunger-contacts, 73—73, preferably formed of German silver, which normally project under their tensional spring control from the face of the insulating plate 72. The line wires or conductors, as at 74—74, of a normally-closed electric circuit comprising a signal or alarm means adapted to be actuated when the circuit is broken, are respectively connected with said plunger-contacts 73. The 35 inner face of the body disc 48 of the operating spindle carries an insulating plate, 75, preferably formed of "bakelite" and annularly surrounding the hub of the spindle, and inlaid in said plate is a segment conductor plate, as at 76, preferably formed of German silver, forming a conductor against which the plungers 73 normally contact. This segment conductor plate is also in circuit connection with the respective line wires or conductors 74—74 of the alarm circuit. Thus, when the operating spindle is in normal position holding the closure plug 29 locked, the alarm circuit is closed, but when the spindle is operatively turned its conductor segment 76 passes off the conductor

plunger contacts 73 and thus immediately opens the circuit and the signal or alarm therein is actuated. It will be understood that the alarm circuit is of itself of any usual or adapted type and extends to any desired point or location exterior of the vault.

To afford an additional protection in the alarm circuit, the line wires or conductors 74—74, in connection with the plunger contacts 73, may be extended in wound position and insulated condition, coiled around the longitudinal length of the main tube or sleeve 18, as illustrated at 77, Fig. 3. Said coiled extension of the conductor wires is 75 resistant to an attack upon the device at any part of its length through or within the body of the vault wall, whereby the wires would be broken or severed and thus open the circuit and cause actuation of the alarm.

The operation and advantages of my invention will be readily understood. The improved air-vent device is at all times normally retained in closed position by engagement of the operating spindle with the closure plug. Under emergency conditions, the 80 only action necessary within the vault to afford instant opening of the air vent for effective ventilation or communication with the exterior, is merely the turning of the operating spindle to release its engagement 85 with the closure plug, whereupon the latter will be instantly and automatically ejected forwardly and entirely clear of the wall-tube or sleeve by expansion of the controlling spring. The improved device thus affords 90 a very simple and effective means which can be instantly operated for automatic action, without any excessive manual operation or lifting or adjustment of heavy parts in the 95 stress of emergency conditions.

I do not desire to be understood as limiting myself to the detail construction and arrangement of parts as herein shown and described, as it is manifest that variations and modifications therein may be resorted to, 100 in the adaptation of my invention to varying conditions of use, without departing from the spirit and scope of my invention and improvements. I therefore reserve the right to all such variations and modifications 105 as properly fall within the scope of my invention and the terms of the following claims.

Having thus described my invention, I claim and desire to secure by Letters Patent: 110

1. An air-vent means of the class described, comprising a tubular body adapted to be secured in a wall and extend therethrough, a plug forming a closure for said tube, means operative at the inner side of 115 the wall for locking said plug in closure position, and means for automatically ejecting the plug from said tube outwardly at the outer side of the wall when said locking means is released.

2. An air-vent means of the class described, comprising a tubular body adapted to be secured in a wall and extend therethrough, said tube having the front end of its bore enlarged or flared outwardly, a plug forming a closure for said tube and having its front end correspondingly enlarged or flared outwardly, means operative at the inner side of the wall for locking said plug through, a plug forming a closure for said tube and having a threaded inner end, means for preventing turning of the plug in said tube, means in threaded engagement with said end of the plug and operative at the inner side of the wall for locking said plug in closure position, and means for automatically ejecting the plug from said tube outwardly at the outer side of the wall when said locking means is released. 75

10 in closure position and holding the enlarged front end to its seat in the tube, and means for automatically ejecting the plug from said tube outwardly at the outer side of the wall when said locking means is released.

15 3. An air-vent means of the class described, comprising a tubular body adapted to be secured in a wall and extend therethrough, a plug forming a closure for said tube, means for preventing turning of the 80 plug in said tube, means operative at the inner side of the wall for locking said plug in closure position and means for automatically ejecting the plug from said tube outwardly at the outer side of the wall when 85 said locking means is released.

20 4. An air-vent means of the class described, comprising a tubular body adapted to be secured in a wall and extend therethrough, means for retaining said tube in fixed position within the wall, a plug forming a closure for said tube, means engaging the inner end of the plug at the inner side of the wall and operative to lock the plug in closure position, and means for automatically 90 ejecting the plug from said tube outwardly at the outer side of the wall when the plug is released from said locking means. 95

25 5. An air-vent means of the class described, comprising a tubular body adapted to be secured in a wall and extend therethrough, tube-locking means engaging the inner end of said tube at the inner side of the wall, a plug forming a closure for said tube, means carried by said tube-locking 100 means and engaging the inner end of the plug and operative to lock the plug in closure position, and means for automatically ejecting the plug from said tube outwardly at the outer side of the wall when the plug is released from said plug-locking means. 105

30 6. An air-vent means of the class described, comprising a tubular body adapted to be secured in a wall and extend therethrough, a plug forming a closure for said tube and having a threaded inner end, means in threaded engagement with said end of the plug and operative at the inner side of the wall for locking said plug in closure position, and means for automatically ejecting the plug from said tube outwardly at the outer side of the wall when said locking 110 means is released. 115

35 7. An air-vent means of the class described, comprising a tubular body adapted to be secured in a wall and extend therethrough, a plug forming a closure for said tube, means for preventing turning of the plug within the tube, means operative at the inner side of the wall for locking said plug in closure position, and a spring tensionally bearing upon said plug and operative to automatically eject the plug from said tube outwardly at the outer side of the wall when said locking means is released. 120

40 8. An air-vent means of the class described, comprising a tubular body adapted to be secured in a wall and extend therethrough, said tube having the front end of its bore enlarged or flared outwardly, a plug forming a closure for said tube and having its front end correspondingly enlarged or flared outwardly, means operative at the inner side of the wall for locking said plug in closure position and holding the enlarged front end to its seat in the tube, and means for automatically ejecting the plug from said tube outwardly at the outer side of the wall when said locking 125 means is released. 130

45 9. An air-vent means of the class described, comprising a tubular body adapted to be secured in a wall and extend therethrough, a plug forming a closure for said tube, means operative at the inner side of the wall for locking said plug in closure position, and a spring tensionally bearing upon said plug and operative to automatically eject the plug from said tube outwardly at the outer side of the wall when said locking means is released. 135

50 10. An air-vent means of the class described, comprising a tubular body adapted to be secured in a wall and extend therethrough, said tube having the front end of its bore enlarged or flared outwardly, a plug forming a closure for said tube and having its front end correspondingly enlarged or flared outwardly, means operative at the inner side of the wall for locking said plug in closure position, and a spring tensionally bearing against said enlarged outer end of the plug and operative to automatically eject the plug from said tube outwardly at the outer side of the wall when said locking means is released. 140

55 11. An air-vent means of the class described, comprising a tubular body adapted to be secured in a wall and extend therethrough, a plug forming a closure for said tube, means for preventing turning of the plug within the tube, means operative at the inner side of the wall for locking said plug in closure position, and a spring tensionally bearing upon said plug and operative to automatically eject the plug from said tube outwardly at the outer side of the wall when said locking means is released. 145

60 12. An air-vent means of the class described, comprising a tubular body adapted to be secured in a wall and extend therethrough, a plug forming a closure for said tube, means for preventing turning of the plug within the tube, means operative at the inner side of the wall for locking said plug in closure position, and a spring tensionally bearing upon said plug and operative to automatically eject the plug from said tube outwardly at the outer side of the wall when said locking means is released. 150

65 13. An air-vent means of the class described, comprising a tubular body adapted to be secured in a wall and extend therethrough, a plug forming a closure for said tube, means for preventing turning of the plug within the tube, means operative at the inner side of the wall for locking said plug in closure position, and a spring tensionally bearing upon said plug and operative to automatically eject the plug from said tube outwardly at the outer side of the wall when said locking means is released. 155

12. An air-vent means of the class described, comprising a tubular body adapted to be secured in a wall and extend therethrough, said tube having the front end of its bore enlarged or flared outwardly, a plug forming a closure for said tube and having its front end correspondingly enlarged or flared outwardly, means for preventing turning of the plug within the tube, means operative at the inner side of the wall for locking said plug in closure position, and a spring tensionally bearing against said enlarged outer end of the plug and operative to automatically eject the plug from said tube outwardly at the outer side of the wall when said locking means is released.
13. An air-vent means of the class described, comprising a tubular body adapted to be secured in a wall and extend therethrough, a plug forming a closure for said tube and having a threaded inner end, turnable means in threaded engagement with said end of the plug and operative at the inner side of the wall for locking said plug in closure position, and a spring tensionally bearing upon said plug and operative to automatically eject the plug from said tube outwardly at the outer side of the wall when said locking means is released.
14. An air-vent means of the class described, comprising a tubular body adapted to be secured in a wall and extend therethrough, said tube having the front end of its bore enlarged or flared outwardly, a plug having a threaded inner end and forming a closure for said tube and having its front end correspondingly enlarged or flared outwardly, turnable means in threaded engagement with the inner end of the plug and operative at the inner side of the wall for locking said plug in closure position, and a spring tensionally bearing against said enlarged outer end of the plug and operative to automatically eject the plug from said tube outwardly at the outer side of the wall when said locking means is released.
15. An air-vent means of the class described, comprising a tubular body adapted to be secured in a wall and extend therethrough, a plug forming a closure for said tube and having a threaded inner end, means for preventing turning of the plug within the tube, turnable means in threaded engagement with said end of the plug and operative at the inner side of the wall for locking said plug in closure position, and

a spring tensionally bearing upon said plug and operative to automatically eject the plug from said tube outwardly at the outer side of the wall when said locking means is released.

16. An air-vent means of the class described, comprising a tubular body adapted to be secured in a wall and extend therethrough, said tube having the front end of its bore enlarged or flared outwardly, a plug having a threaded inner end and forming a closure for said tube and having its front end correspondingly enlarged or flared outwardly, means for preventing turning of the plug within the tube, turnable means in threaded engagement with the inner end of the plug and operative at the inner side of the wall for locking said plug in closure position, and a spring tensionally bearing against said enlarged outer end of the plug and operative to automatically eject the plug from said tube outwardly at the outer side of the wall when said locking means is released.

17. An air-vent means of the class described, comprising a tubular body adapted to be secured in a wall and extend therethrough, a plug forming a closure for said tube, means operative at the inner side of the wall for locking said plug in closure position, an extension plug carried at the outer end of said main plug to compensate for extra wall thickness, and means for automatically ejecting the plug member from said tube outwardly at the outer side of the wall when said locking means is released.

18. An air-vent means of the class described, comprising a tubular body adapted to be secured in a wall and extend therethrough, a plug forming a closure for said tube, means operative at the inner side of the wall for locking said plug in closure position, a supplementary tube extending from the outer end of said main tube, an extension plug carried at the outer end of said main plug and within said extension tube, said extension tube and extension plug compensating for extra wall thickness, and means for automatically ejecting the plug member from said tube outwardly at the outer side of the wall when said locking means is released.

In testimony whereof I have signed the foregoing specifications.

JOHN P. WILLIAMS.
